 Switzerland

Application December 7, 1934, Serial No. 756,409
 In Germany December 8, 1933

14 Claims. (Cl. 175—363)

This invention relates in general to electric valve protective systems, and more particularly to systems for preventing the occurrence of disturbances in an electric valve during establishment of the conductive condition of the cathode of the valve by means of an ignition electrode.

Electric valves of the type in which the cathode is maintained in conductive condition by the flow of an excitation discharge therethrough, are generally brought into the conductive condition by means of an ignition electrode momentarily engaging with the cathode. During operation of the valve, the discharge therein may be momentarily interrupted, so that the cathode loses its conductivity and the ignition electrode must be operated to reestablish the conductive condition. If the main electrodes of the valve are connected with the associated source and with the load circuit at such time, a circuit may be established from a main anode of the valve to the cathode by way of the ignition electrode and of the energizing circuit therefor, and a flow of working current may occur through such a circuit with the result that the apparatus connected therein may be damaged or even destroyed. It is therefore necessary to delay the flow of current through the main anodes of the valve until after the ignition operation of the valve has been completed, such result being preferably obtained by employing control electrodes operable to prevent the flow of current through the associated anodes. Such control electrodes are preferably so energized that the flow of current through the valve is then released at a gradually increasing voltage to avoid the voltage surge resulting from the sudden impression of full voltage on the load, which may be detrimental to loads of certain particular types.

It is, therefore, one of the objects of the present invention to provide an electric valve protective system by which the control electrodes of the valve neutralize the conductivity of the valve when the excitation discharge thereof is not established.

Another object of the present invention is to provide an electric valve protective system by which the valve is made non-conductive upon failure of the excitation discharge thereof.

Another object of the present invention is to provide an electric valve protective system by which the flow of current through the valve is established at a gradually increasing voltage after interruption of the operation of the valve.

Objects and advantages other than those above set forth will be apparent from the following

description when read in connection with the accompanying drawing, which diagrammatically illustrates one embodiment of the present invention applied to the protection of an electric valve utilized in an alternating current rectifying system.

Referring more particularly to the drawing by characters of reference, reference numeral 2 generally designates an electric valve utilized for controlling the flow of current between an alternating current line 3 and a direct current line 4. It will be understood, however, that the nature of the working circuits connected with the valve is immaterial for the present invention, so that the valve may be utilized for other purposes than for the rectification of alternating current. In the present embodiment, valve 2 is connected with line 3 through a transformer 6, the connection between line 3 and transformer 6 preferably including a circuit breaker 7. Valve 2 is provided with a plurality of main anodes 8 severally connected with the phase portions of the secondary winding of transformer 4, and with a cathode 9 connected with one of the conductors of line 4. Cathode 9 preferably consists of a body of liquid mercury, which is brought to conductive condition by momentary engagement thereof with an ignition electrode 11 receiving current from a transformer 12 energized from line 3 through a switch 13. After a cathode spot is thus established on cathode 9, the cathode is maintained in conductive condition by the flow therethrough of an excitation discharge from excitation anodes 14 connected with transformer 12 through resistors 15.

The engagement of electrode 11 with cathode 9 is obtained by the action of a solenoid 16 acting against a spring 17. The solenoid is energized from transformer 12 through the contacts of a relay 18. Ignition electrode 11 receives current from transformer 12 through contacts 20 of another relay 19 and through a resistor 21, the circuit being completed through cathode 9, coils of relays 18 and 19, and a reactor 22 to a midtap of the secondary winding of transformer 12. The coil of relay 18 is so dimensioned as to cause operation of the relay upon establishment of a flow of current through electrode 11, and the coil of relay 19 is so dimensioned as to cause operation of the relay only upon flow therethrough of the considerably larger current of excitation anodes 14.

The operation of each main anode 8 is controlled by means of an associated control electrode 23 which may be energized in any suitable

manner known in the art. Each control electrode is preferably connected through a resistor 24 with one of the phase portions of the secondary winding 27 of a transformer 26 having a primary winding 28. Winding 27 is connected in star to form a neutral point normally maintained at a negative potential with respect to the potential of cathode 9 by means of a suitable source of negative unidirectional voltage such as a battery 29. The battery may be connected directly between the neutral point and the cathode, or such connection may be effected through a voltage divider 31. Battery 29 may be disconnected from the circuits energized therefrom by means of a switch 32 preferably connected with switch 13 so that those switches must be simultaneously closed.

Winding 28 is preferably connected with line 3 through a step-down insulating transformer 33 and through impedance means such as resistors 34, the purpose of which will appear hereinafter. Each phase of line 3 also supplies, through a resistor 34, the working winding of a reactor 35 having a saturating winding 36. The several windings 36 receive current from voltage divider 31 through contacts 37 of relay 19, a resistor 38, contacts 39 of a relay 41, and through an electric valve 42 of the discontinuous control type having a cathode connected at an intermediate point of voltage divider 31. Valve 42 is provided with a control electrode connected with the positive terminal of voltage divider 31 through a resistor 43 and through contacts 44 of relay 19. The coil of relay 41 is connected with contacts 37 of relay 19 and is connected with an intermediate point of resistor 38 through contacts 46 of the relay 41. Contacts 46 are arranged to close before contacts 39 are opened as a result of the operation of relay 41. Voltage divider 31 and contacts 44 are bridged by a resistor 47 in series with another resistor 48 receiving unidirectional current from a current transformer 49 inserted in the connection between line 3 and transformer 6, such current being rectified by suitable rectifying devices 51. Relay 19 is provided with further contacts 52 connecting voltage divider 31 with the closing coil 53 of circuit breaker 7. The circuit breaker may be maintained in the closed position by means of a latch maintained in engagement by means of a low-voltage trip coil 54 energized from line 3 through switch 13.

In operation, the system being connected as shown and line 3 being energized, valve 2 is put in operation by closure of switches 13 and 32. Upon closure of switch 32 the control electrode of valve 42 receives a negative potential with respect to the potential of the associated cathode as a result of the connection thereof with voltage divider through resistors 43, 47 and 48. Such potential is, however, overcome by the positive potential impressed on the control electrode from voltage divider 31 through contacts 44, so that valve 42 becomes conductive. A flow of current is thus initiated from the positive terminal of voltage divider 31 through contacts 37, windings 36, resistor 38, contacts 39 and valve 42 to voltage divider 31. Such flow of current through windings 36 causes the cores of reactors 35 to become saturated, so that the working windings of the reactors draw comparatively large currents from line 3 through resistors 34. Such flow of current causes a comparatively large voltage drop in resistors 34, with the result that the voltages of the several portions of winding 27,

induced therein from winding 28, are caused to lag and to decrease in value to an extent such that their amplitude becomes less than the value of the unidirectional voltage impressed between cathode 9 and the neutral point of winding 27. The control electrodes 23 are thus maintained at variable negative potentials with respect to cathode 9, and prevent any flow of current through anodes 8 even if circuit breaker 7 is closed and cathode 9 is made conductive.

At the same time, closure of switch 13 has caused transformer 12 to become energized, and the transformer supplies current to solenoid 16 through the contacts of relay 18. The solenoid accordingly urges ignition electrode 11 downward into engagement with cathode 9. Upon engagement of the electrodes, a circuit is completed from transformer 12 through contacts 20, resistor 21, spring 17, electrode 11, cathode 9, coils of relays 18 and 19 and reactor 22 to the mid-tap of the secondary winding of transformer 12. A flow of alternating current accordingly occurs through such circuit, and relay 18 operates to open the contacts thereof, thereby deenergizing solenoid 16. Ignition electrode 11 is then withdrawn from cathode 19 under the action of spring 17. Upon separation of the electrodes, the flow of current therebetween tends to continue in the form of a discharge, such discharge momentarily occurring in a direction depending upon the momentary polarity of transformer 12, and causing establishment of a cathode spot on the particular electrode which is negative with respect to the other electrode at the moment of their separation.

The cathode spot may thus be established on electrode 11 and if, at such instant circuit breaker 7 were closed and control electrodes 23 were positively energized, a current could flow from transformer 6 through anodes 8, electrode 11, spring 17, resistor 21, contacts 20, transformer 12, reactor 22, coils of relays 19 and 18 through line 4 and the load devices connected therewith back to transformer 6. Such flow of current would occur at the working voltage of the line and would therefore be apt to damage or even destroy the apparatus connected in the ignition circuit. Circuit breaker 7 being open and control electrodes 23 being negative, such flow of current cannot take place and the flow of current from cathode 9 to electrode 11 ceases upon reversal of the voltage impressed therebetween. Relay 18 then returns to the position shown, and the operation of ignition electrode 11 is repeated until the separation of electrode 11 and cathode 9 occurs at an instant such that a cathode spot is established on the cathode.

When such cathode spot is established, an excitation discharge occurs from electrodes 14 to cathode 9, the discharge of the two excitation anodes combining at the cathode to form a flow of direct current which is maintained at a substantially uniform value as a result of the action of reactor 22. Such flow of current is of sufficient magnitude to cause relay 19 to operate to close contacts 52. Closure of such contacts causes closing coil 53 to be energized from voltage divider 31, so that circuit breaker 7 closes, and is maintained in the closed position by means of the latch maintained in engagement therewith by coil 54 energized from line 3. At such time, the flow of current through main anodes 8 of valve 2 is still prevented by the action of control electrodes 23. Relay 19 also opens the circuit of ignition electrode 11 at contacts 20, so

that the electrode becomes entirely inoperative. Relay 19 also opens contact 44, so that the control electrode of valve 42 is disconnected from the positive terminal of voltage divider 31, and such control electrode becomes negative with respect to the associated cathode but is unable to render valve 42 non-conductive until the flow of current therethrough has been interrupted at contacts 39 of relay 41. Relay 19 also opens contacts 37, thereby removing the short circuit across the coil of relay 41. The relay therefore operates to close contacts 46, thereby connecting windings 36 in a closed circuit with coil of relay 41 and a portion of resistor 38. The magnetic energy stored in the cores of reactors 35 then is gradually dissipated in the form of a flow of current of sufficient magnitude to cause relay 41 to continue its movement to open contacts 39 and thereby enable valve 42 to return to the non-conductive condition. The flow of current through windings 36 gradually decreases at a rate depending upon the amount of resistor 38 inserted in circuit therewith, with the result that the cores of the reactors are gradually desaturated and the inductance of the reactors gradually increases. The flow of current drawn by the working windings of the reactors through resistors 34 thus gradually decreases, thereby causing a proportional decrease in the voltage drop caused by such current flow in resistors 34. As a result of such action, the voltages of the phase portions of winding 27 gradually increase in magnitude and advance in phase. When the amplitude of such voltages is equal to the negative potential of the neutral point of winding 27 with respect to the potential of cathode 9, each control electrode 23 periodically becomes positive at a comparatively late instant in the voltage cycle of the associated anode, and the flow of current through valve 2 is released at the lowest possible voltage. Upon further increase of the magnitude of the voltages of winding 27 and further advance in their phase, the flow of current through each anode 8 is released at increasingly leading instants of the voltage cycle until windings 36 are without current, at which time the flow of current through valve 2 is released at the maximum possible voltage. Relay 41 then returns to the position shown. The starting operation of valve 2 is then completed and the flow of current therethrough occurs at a predetermined voltage in relation with the voltage of line 3, and its intensity depends on the value of the impedance of the load connected with line 4.

55 During such operation of valve 2, a sudden decrease of the load current in the valve to zero, or even a sudden decrease from a high value to a low value may cause the discharge in valve 2 to become unstable, so that the flow of current through both main anodes 8 and excitation anodes 14 may be interrupted. The cathode is then no longer maintained in the conducting condition, and the excitation current cannot be re-established until renewed operation of ignition electrode 11. Upon such interruption of the excitation current, relay 19 returns to the position shown, thereby opening contacts 52. Circuit breaker 7 however, remains in the closed position because coil 54 is still energized from line 3 and maintains the latch in engagement with the circuit breaker. Contacts 37 and 44 of relay 19 are again closed with the result that control electrodes 23 are again made negative with respect to cathode 9 in the manner above explained.

70 Relay 18 also returns to the position shown to

again initiate operation of ignition electrode 11 in manner above explained.

If the control electrodes 23 were positive, the occurrence of a cathode spot on ignition electrode 11 would then cause a flow of load current to occur through such ignition electrode, the ignition circuit, and the load circuit, thereby damaging or even destroying the ignition and excitation apparatus. Negative energization of control electrodes 23, however, will prevent this occurrence and, after one or more operations of ignition electrode 11, a cathode spot is established at cathode 9 and the flow of excitation current from excitation anode 14 to cathode 9 is reestablished as above explained. Relay 19 then again operates and causes the flow of current through valve 2 to be released at a gradually increasing voltage.

Upon occurrence of a disturbance in the system resulting in an excessive flow of current through current transformer 49, the voltage appearing across the terminals of resistor 48 becomes of sufficient magnitude to cause the control electrode of valve 42 to become positive with respect to the associated cathode. Valve 42 thus becomes conductive and completes the connections between voltage divider 31 and windings 36, such connections now including the coil of relay 41. The cores of reactors 35 are thus rapidly saturated, resistor 38 being of a comparatively high resistance to impart a generally resistive character to the circuit of windings 36. As a result of the saturation of reactors 35, control electrodes 23 are brought to variable negative potentials with respect to the potential of cathode 9, thereby causing the flow of current through main anodes 8 to cease as is well known in the art. The core of relay 41 being energized, the relay operates, and its operating speed is so adjusted that contacts 46 are closed only when the flow of current has already ceased through main anode 8. Upon closure of contacts 46, the reactors are gradually desaturated and the flow of current through main anodes 8 of valve 2 is reestablished at a gradually increasing voltage as above explained.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In combination, an electric valve having a main anode with an associated control electrode, a cathode, an ignition electrode and an excitation anode, a voltage source connectible with said ignition electrode and with said excitation anode and with said cathode, means including a source of control voltage for impressing on said control electrode potential of sign and magnitude effective to prevent initiation of the flow of current between said main anode and said cathode, and means responsive to the flow of current through said excitation anode and initiated by the operation of said ignition electrode for rendering ineffective the first said means.

2. In combination, an electric valve having a main anode with an associated control electrode, a cathode, an ignition electrode and an excitation anode, a voltage source connectible with said ignition electrode and with said excitation anode and with said cathode, a switch for connecting said anode with said source, means including a source of control voltage for impress-

- ing on said control electrode potential of sign and magnitude effective to prevent initiation of the flow of current between said main anode and said cathode, and means responsive to the flow of current through said excitation anode and initiated by the operation of said ignition electrode for rendering ineffective the first said means and for controlling the closure of said switch.
3. In combination, an electric valve having a main anode with an associated control electrode, a cathode and an excitation anode, a supply circuit and a load circuit interconnected by way of said anode and said cathode whereby said load circuit receives current at a voltage of predetermined value, a voltage source connectible with said excitation anode and said cathode to cause a flow of current therebetween, a source of control voltages for said control electrode, means for impressing between said control electrode and said cathode a voltage effective to prevent the flow of current between said main anode and said cathode, and means responsive to the flow of current between said excitation anode and said cathode for impressing between said control electrode and said cathode a voltage effective to release the flow of current between said main anode and said cathode at a variable voltage gradually increasing to said predetermined value.
- 30 4. In combination, an electric valve having a main anode with an associated control electrode, a cathode and an excitation anode, a source of alternating current connected with said excitation anode and said cathode to cause a flow of rectified current therebetween, a source of negative unidirectional voltage connected with said cathode, a transformer having a primary winding connected with the first said source and a secondary winding connecting the second said source with said control electrode to periodically release the flow of current between said main anode and said cathode, and means responsive to failure of the flow of current between said excitation anode and said cathode for rendering said transformer ineffective to thereby cause said control electrode and the second said source to prevent the flow of current between said main anode and said cathode.
5. In combination, an electric valve having a main anode with an associated control electrode, a cathode and an excitation anode, a source of alternating current connected with said excitation anode and said cathode to cause a flow of rectified current therebetween, a source of negative unidirectional voltage connected with said cathode, a transformer having a primary winding connected with the first said source and secondary winding connecting the second said source with said control electrode to periodically release the flow of current between said main anode and said cathode, and means responsive to failure of the flow of current between said excitation anode and said cathode for reducing the amplitude of the voltage of said secondary winding to less than the value of the voltage of the second said source, whereby said control electrode is maintained at a variable negative potential to cause interruption of the flow of current between said anode and said cathode.
6. In combination, an electric valve having a main anode with an associated control electrode, a cathode and an excitation anode, a source of alternating current connected with said excitation anode and said cathode to cause a flow of rectified current therebetween, a source of negative unidirectional voltage connected with said cathode, a transformer having a primary winding connected with the first said source and a secondary winding connecting the second said source with said control electrode to periodically release the flow of current between said main anode and said cathode, impedance means in the connection between said primary winding and the first said source, a reactor connected with the first said source through said impedance means, and means responsive to failure of the flow of current between said excitation anode and said cathode for saturating the core of said reactor to thereby render said transformer ineffective to thereby cause said control electrode and the second said source and prevent initiation of the flow of current between said main anode and said cathode and for gradually returning the core of said reactor to the normal magnetic condition thereof upon renewed flow of current between said excitation anode and said cathode.
7. In combination, an electric valve having a main anode with an associated control electrode, a cathode and an excitation anode, a source of alternating current connected with said excitation anode and said cathode to cause a flow of rectified current therebetween, a source of negative unidirectional voltage connected with said cathode, a transformer having a primary winding connected with the first said source and a secondary winding connecting the second said source with said control electrode to periodically release the flow of current between said main anode and said cathode, impedance means in the connection between said primary winding and the first said source, a reactor connected with the first said source through said impedance means, and means responsive to failure of the flow of current between said excitation anode and said cathode for saturating the core of said reactor to thereby cause said control electrode and the second said source and prevent initiation of the flow of current between said main anode and said cathode and for gradually returning the core of said reactor to the normal magnetic condition thereof upon renewed flow of current between said excitation anode and said cathode.
8. In combination, an electric valve having a main anode with an associated control electrode, a cathode and an excitation anode, a source of alternating current connected with said excitation anode and said cathode to cause a flow of rectified current therebetween, a source of negative unidirectional voltage connected with said cathode, a transformer having a primary winding connected with the first said source and a secondary winding connecting the second said source with said control electrode to periodically release the flow of current between said main anode and said cathode, impedance means in the connection between said primary winding and the first said source, a reactor connected with the first said source through said impedance means, and means responsive to failure of the flow of current between said excitation anode and said cathode for saturating the core of said reactor to thereby render said transformer ineffective to thereby cause said control electrode and the second said source and prevent initiation of the flow of current between said main anode and said cathode and for gradually returning the core of said reactor to the normal magnetic condition thereof upon renewed flow of current between said excitation anode and said cathode.
9. In combination, an electric valve having a main anode with an associated control electrode, a cathode and an excitation anode, a supply circuit and a load circuit interconnected by way of said anode and said cathode whereby said load circuit receives current at a voltage of predetermined value, a voltage source connectible with said excitation anode and said cathode to cause a flow of current therebetween, a source of negative unidirectional voltage connected with said cathode, a transformer having a primary winding connected with the first said source and a secondary winding connecting the second said source with said control electrode to periodically release the flow of current between said main anode and said cathode, impedance means in the connection between said primary winding and the first said source, a reactor connected with the first said source through said impedance means, and means responsive to failure of the flow of current between said excitation anode and said cathode for saturating the core of said reactor to thereby render said transformer ineffective to thereby cause said control electrode and the second said source and prevent initiation of the flow of current between said main anode and said cathode and for gradually returning the core of said reactor to the normal magnetic condition thereof upon renewed flow of current between said excitation anode and said cathode.

of control voltages for said control electrode, means for impressing between said control electrode and said cathode a voltage effective to release the flow of current between said main anode and said cathode, and means responsive to failure of the flow of current through said excitation anode and to the occurrence of flow of excessive current through said main anode for impressing between said control electrode and said cathode a voltage effective to prevent initiation of the flow of current through said main anode.

10. In combination, an electric valve having a main anode with an associated control electrode, a cathode and an excitation anode, a source of alternating current connected with said excitation anode and said cathode to cause a flow of rectified current therebetween, a source of negative unidirectional voltage connected with said cathode, a transformer having a primary winding connected with the first said source and a secondary winding connecting the second said source with said control electrode to periodically release the flow of current between said main anode and said cathode, impedance means in the connection between said primary winding and the first said source, a reactor connected with the first said source through said impedance means and having a saturating winding, an auxiliary electric valve connecting said saturating winding with the first said source, and means responsive to failure of the flow of current between said excitation anode and said cathode for rendering said valve conductive.

11. In combination, an electric valve having a main anode with an associated control electrode, a cathode, and an excitation anode, a voltage source connecting said excitation anode with said cathode to cause a flow of current therebetween, means exclusive of said source including a second voltage source for impressing between said control electrode and said cathode a voltage effective to release the flow of current between said main anode and said cathode, and means responsive to failure of the flow of current between said excitation anode and said cathode including a third voltage source for impressing between said control electrode and said cathode a voltage effective to prevent initiation of the flow of current between said main anode and said cathode.

12. In combination, an electric valve having a main anode with an associated control electrode, a cathode, and an excitation anode, a voltage source connecting said excitation anode with said cathode to cause a flow of current therebetween, means exclusive of said source including a second voltage source for impressing between said control electrode and said cathode a voltage effective to continually control the moments of initiation of the flow of current between said main anode and said cathode, and means responsive to failure of the flow of current between said excitation anode and said cathode including a third voltage source for impressing between said control electrode and said cathode a voltage effective to prevent initiation of the flow of current between said main anode and said cathode.

13. In combination, an electric valve having a main anode with an associated control electrode, a cathode, and an excitation anode, a voltage source connecting said excitation anode with said cathode to cause a flow of current therebetween, means exclusive of said source including a second voltage source for energizing said control electrode, and means including means responsive to failure of the flow of current between said excitation anode and said cathode for impressing between said control electrode and said cathode a voltage from the second said source effective to prevent initiation of the flow of current between said main anode and said cathode.

14. The combination with an electric valve comprising a main anode, a cathode, a control electrode, and an excitation anode, means comprising a source of potential for causing the flow of current between said cathode and excitation anode, means comprising a source of current for impressing on said control electrode potential of such sign and magnitude as to prevent the initiation of flow of current between said main anode and cathode, and means comprising a source of current for impressing on said control electrode potential of such sign and magnitude as to render ineffective the second said means, of means operable responsive to the said flow of current between said cathode and said excitation anode for rendering effective the third said means.
